PHASE ADJUSTING APPARATUS

Austin G. Cooley, New York, N. Y., assignor to
Times Facsimile Corporation, a corporation of
New York

Original application October 28, 1943, Serial No.
508,041, now Patent No. 2,411,147, dated No-
vember 19, 1946. Divided and this application
August 31, 1946, Serial No. 694,392

4 Claims. (Cl. 323—119)

1

This invention relates to phase-adjusting apparatus for alternating-current systems.

The object of the invention is to provide improved control means for phase-adjustment of electric currents, to enable the phase of an alternating-current wave to be varied through a range of 360° or more. The control apparatus embodying the invention is useful in various systems including remote-control systems of the type disclosed in my prior Patent Number 2,411,147 granted November 19, 1946, which the present application is a division.

Another object of the invention is to provide phase or frequency-adjusting apparatus of this character which may be controlled by a small amount of energy or power input and permit smooth, rapid adjustment over a wide range, if desired.

In describing my invention in detail and to bring out further objects and advantages thereof, reference will be made to the attached drawing illustrating two preferred embodiments of the invention. In the drawings, Fig. 1 is a diagrammatic view of a remote-control system employing phase-adjusting apparatus; Figs. 2 and 3 are detail views of a phase-adjusting arrangement employing optical elements; and Fig. 4 is a similar view of a modification.

Referring to Fig. 1 of the drawings, a remote-control system is illustrated in this figure comprising two single-phase synchronous motors 11 and 12 adapted to be continuously driven by alternating currents of two different frequencies transmitted over a control circuit 13. An oscillator 15 is shown by way of example as a source of current for operating the motors 11 and 12. The oscillator 15 is connected through a phase-shifting apparatus 16 to a primary winding 17 of a transformer 18. The phase-shifter 16 is provided with suitable means, such as a manually operable handwheel 21, for varying the phase relation between the input and output currents through said phase-shifting device. The oscillator 15 is also connected through a frequency-changer 22 in order to impress an alternating current of another constant frequency upon the second primary winding 23 of the transformer 18. Thus currents of two different frequencies, one constant and one variable by operation of the phase-shifter 16, are induced in the secondary winding 24 of the transformer which is connected to the control circuit 13.

The frequencies of the currents supplied by the transformer 18 to the control circuit are preferably in the audio range between a few

2

hundred and a few thousand cycles, such frequencies being readily separated at the receiving end of the system by filters 25 and 26 to operate the associated synchronous motors at speeds corresponding to the frequencies of the separate control currents. As indicated, amplifiers 27 and 28 may be provided if desired, between the filters and the respective motors 11 and 12.

The motors may be of the reluctance or phonic wheel type similar to that described in my prior Patent #2,257,158, dated September 30, 1941. A motor of this type is designed to deliver substantial power when the frequency of the applied current is of the order of one or two thousand cycles. The frequency of the oscillator 15 may, for example, be 1800 cycles per second and the output of the frequency-changer 22 may be a constant frequency of 1200 cycles per second. The two motors 11 and 12 at the receiving station are connected through differential gearing 31 to an index or movable arm 32, the position of which is to be controlled by adjustment of the movable control member 21 at the remote transmitting station. If the motors 11 and 12 have the same numbers of poles so that they run at different speeds, gearing 33 may be provided to drive the differential gearing at the proper speed relation so that the control member 32 will be fixed in position at a predetermined ratio of the control current frequencies in the control circuit 13. Alternatively, the motors 11 and 12 may be constructed with different numbers of poles and the gearing 33 omitted.

In a system of this character, as explained in my prior patent above referred to, the member 32 may be positioned or moved precisely in accordance with the adjustment of the phase-shifting means 16 and the accuracy of control is not affected by variations in the supply voltage or the resistance, inductance or leakage resistance of the control circuit 13. Considerable power is available at the differentially-controlled member, if required, and this power need not be transmitted over the control circuit. The phase-shifting means according to the present invention finds an important application in control systems of this type although it may be used in other alternating-current systems.

A preferred construction of the phase-shifting means 16 is illustrated in Figs. 2 and 3, this means employing a series of translating devices 35, 36, 37 and 38, shown as photocells. In this modification a pivoted disc or vane 41 having a series of equally-spaced holes 42 around its periphery is employed as a light-directing member

to vary the light excitation of the photocells as the disc rotates. The disc 41 is arranged or connected to be turned by a manual or mechanically-operated control element to effect phase adjustment and only sufficient power is required to overcome the friction of the disc journal or pivot. In the particular embodiment illustrated, a fluctuating light source 44 is arranged to illuminate the photocells 35, 36, 37 and 38 in succession as the disc 41 is turned. The light source 44 may be a neon glow-discharge or arc-discharge lamp connected to an alternating-current supply circuit of constant frequency such as the oscillator 18 whereby a pulsating light of constant frequency is obtained. The optical system shown including plano-convex lenses 45 and 46 and a light shield 47 is constructed and arranged to cause the beam of light which passes through each hole in the disc 41 to sweep progressively over the photocells one after the other as the disc is turned. The lenses and the shield are correlated with the size and spacing of the holes 42 and the location and extent of the cathodes of the photocells to insure that the total output current from the cell or cells illuminated at any instant remains substantially constant. As shown, the spacing of the holes 42 is such that as one hole moves past the edge of the opening in the shield 47, the adjacent hole permits light from the source 44 to strike one of the end cells. Thus the photocells are successively illuminated with pulsating light from the lamp 44, always in the sequence 38-37-36-35, when the holes in the disc 41 traverse the light field in the direction indicated by the arrow, and in the sequence 35-36-37-38 for the opposite rotation of the disc 41. This successive energization of the photocells 35-38 is utilized to obtain a signal wave, the phase of which varies in accordance with the movement of the disk 41 in the following manner.

In accordance with the invention, the output currents of the respective cells 35 to 38 are phase-controlled in a predetermined manner and combined in the primary winding of an output transformer 49. A control voltage is generated in the secondary winding of the transformer 49 so that alternating current flows in the output circuit connected thereto which is shifted in phase as the disc 41 is turned. As shown, a conventional two-stage amplifier comprising tubes 51 and 52 is provided for the photocell 35. A similar amplifier 53, 54 is provided for the photocell 36 except that a condenser 55 is connected in the input circuit of the tube 53 to displace the output current of the amplifier 90° with respect to that of the amplifier 51, 52. Likewise, the amplifier 56, 57 for the photocell 37 includes a coupling transformer 58 so that the output current of the amplifier is displaced 180° with respect to that of the amplifier 51, 52; and the amplifier 59, 60 for the photocell 38 is similar to the amplifier 56, 57 except for the condenser 61 arranged to effect a further phase-adjustment of 90° or a total of 270° with respect to the output current from the first photocell 35. The phase-control arrangement illustrated is preferred but modified arrangements may be employed which embody similar principles in carrying out the invention.

With this arrangement it will be evident that, as the light beam from the light source 46 is deflected progressively over the series of photocells, an output current is generated in the secondary of the transformer 49 which shifts in phase

through 360° for each traverse of the light beam across all of the photocells and which is of a frequency corresponding to that of the intermittent or fluctuating light source 44. The output current is of a frequency which can be readily amplified in a vacuum tube amplifier and preferably is between several hundred and several thousand cycles. In particular cases, other frequencies and different circuits may be employed for combining the output currents of the photocells to obtain a phase-shift.

A modified form of phase-shifting means which embodies the invention is illustrated in Fig. 4. As in the first modification described above, this construction is designed to operate on a small torque or operating force, and is arranged to provide a continuous phase-shift in either direction through a range of 360° or more. The phase-shift apparatus shown in Fig. 4 comprises a movable control member 64 in the form of a plate or vane which is integral with or secured to a compass or other control element. The movable vane 64 is provided with spaced iron inserts 65 supported for movement along a row of translating devices in the form of stationary electromagnets 66, 67, 68 and 69. The spacing between the inserts 65 is such that as the right-hand edge of one insert is moved to the middle of the core of the magnet 66, the left-hand edge of the next insert lies above the middle of the core of the magnet 69, and the width of the insert is substantially equal to the distance between the central axes of adjacent magnet cores so that the magnetic flux induced in the inserts 65 remains constant as the vane 64 is moved (assuming that the electromagnets are of equal strength).

The electromagnets 66, 67, 68 and 69 are connected to an alternating-current supply circuit 71, for example, of a frequency of the order of one or two thousand cycles. However, a condenser 72 is connected in series with electromagnet 67 to displace the phase of the current traversing its coil 90°. Similarly, means such as a transformer 73 and a condenser 74 is provided to displace the phase of the currents traversing the electromagnets 68 and 69 by 180° and 270°, respectively, with reference to the current traversing the electromagnet 66. Consequently it will be apparent that the algebraic sum of the fluxes in the insert 65 opposite the electromagnets is shifted in phase through 360° as the insert is moved from a position approaching the magnet 66 to a position beyond the magnet 69 or vice versa. A stationary magnetizable core 75 opposite the electromagnets 66 to 69 carries a pickup coil 76 in which current of the same frequency as that of the supply circuit 71 is induced, said current being retarded or advanced in phase 360° as each insert 65 moves past the core 75. The terminals of the pickup coil 76 are connected to the output or utilization circuit, such for example as represented by the primary winding 77 of the transformer 18 in the remote-control system illustrated in Fig. 1.

While the two embodiments of the invention have been illustrated to explain the fundamental principles thereof, other modifications will occur to those skilled in the art and may be made without departing from the scope of the invention as defined in the appended claims.

I claim:

1. In an alternating-current system of the character described, a source of alternating cur-

rent and phase-shifting means connected to said source, said phase-shifting means comprising a light source connected to said alternating-current source to produce a fluctuating light output, photocell means operatively associated with said light source, means including a rotatable light-directing member to vary progressively the illumination of the photocell means and means to obtain a variable-phase alternating current from said photocell means.

2. In an alternating-current system of the character described, a source of alternating current and phase-shifting means connected to said source, said phase-shifting means comprising a fluctuating light source, a series of photocells arranged side by side, a movable light-directing member between said light source and said photocells arranged to vary progressively and in predetermined sequence the illumination of the respective photocells and means in circuit with said photocells for deriving an alternating current the phase of which is dependent on the position of said movable member, said last-mentioned means including separate amplifiers for said photocells each having different phase-shifting characteristics.

3. In an alternating-current system of the character described, a source of alternating current and phase-shifting means connected to said source, said phase-shifting means comprising cyclically varying light-generating means, a series of photocells operatively associated therewith, a movable light controlling vane between said

light-generating means and said cells and arranged to effect progressive and cyclical illumination of different ones of the cells as the vane moves, an output circuit and separate circuits of different phase-shift characteristics connected between each of said photocells and the output circuit to cause the phase of the current in said output circuit to depend upon the particular cell which is operative.

10 4. Phase-shifting apparatus comprising a plurality of circuits of differing phase-shift characteristics, a common output circuit connected to said other circuits and light-sensitive means for energizing any of said first-mentioned circuits, to produce a current flow in the output circuit of corresponding phase.
